UNITED STATES PATENT OFFICE.

WILLIAM S. JONES, OF MORGANTOWN, WEST VIRGINIA, ASSIGNOR TO
ECONOMY TUMBLER COMPANY, OF MORGANTOWN, WEST VIRGINIA,
A CORPORATION OF WEST VIRGINIA.

DESIGN FOR A GLASS VESSEL.

No. 38,346.

Specification for Design.

Patented Dec. 11, 1906.

Application filed November 8, 1906. Serial No. 342,581. Term of patent 7 years.

To all whom it may concern:

Be it known that I, WILLIAM S. JONES, a citizen of the United States, residing at Morgantown, in the county of Monongalia, State of West Virginia, have invented a new, original, and ornamental Design for Glass Vessels, of which the following is a specification, reference being had to the accompanying drawings, in which—

Figure 1 is a perspective view of a glass

vessel, showing my new design; and Fig. 2 is a perspective view thereof at right angles to Fig. 1.

I claim—

The ornamental design for a glass vessel, as shown.

WILLIAM S. JONES.
